2 Sheets-Sheet 2

UNITED STATES PATENT OFFICE.

JOHN EKLUND, OF ST. JOSEPH, MICHIGAN, ASSIGNOR TO ST. JOSEPH IRON WORKS, OF ST. JOSEPH, MICHIGAN, A CORPORATION OF MICHIGAN.

HOOP GUIDE.

Application filed June 29, 1923. Serial No. 648,561.

To all whom it may concern:

Be it known that I, JOHN EKLUND, a citizen of the United States, residing at St. Joseph, in the county of Berrien and State of Michigan, have invented new and useful Improvements in Hoop Guides, of which the following is a specification.

My invention aims to provide an improved hoop guide for basket stapling machines, whereby a hoop of the exact length required will be guided straight and will be wound tightly about the edge of the basket preceding the stapling operation.

In the accompanying drawing, wherein I have shown one embodiment of my invention for purpose of illustration,

Figure 1 is a perspective view of the improved hoop guide and so much of a stapling machine as is necessary for an understanding of the invention;

Figure 2 is a front view showing less of the stapling machine than is shown in Fig. 1;

Figure 3 is a plan view of the hoop guide, with a portion of the stapling machine;

Figure 4 is an inverted plan view of the finger extension; and

Figure 5 is an edge view of the same.

In the particular embodiment of my invention selected for illustration herein and shown in the drawings, there is shown part of an automatic berry basket stapling machine, including the lower portion of the stapling head 3, and the basket form or holder 5, which is revolved intermittently in the direction of the arrow by shaft 7 during the stapling operation.

The frame of the machine (not shown) has an extension 9 providing a bearing 11 for an adjusting shaft 13, said shaft being retained in the bearing 11 preferably by a set screw 15. One end of shaft 13 mounts a casting 17 by means of a reduced eccentric end 19, a set screw 21 providing a convenient means by which casting 17 may be secured upon the eccentric end portion 19 of the adjusting shaft 13. When the casting 17, which with certain associated parts acts as a hoop guide, is to be raised or lowered relative to the form 5 upon which the basket

is stapled, it is only necessary to turn shaft 13 whereupon the eccentric end 19 will be turned and the position of the hoop guide will be adjusted.

The casting 17 has a flange 23 projecting from one face thereof and serving as a ledge to guide the hoop strip as it is fed to the stapling mechanism by the operator. Preferably the upper surface of flange 23 is approximately on a level with the upper end of form 5 when the casting 17 is adjusted in its uppermost position, as shown in Fig. 2, so that the hoop passes from the guiding flange 23 to the form without considerable bending or change in direction. Should a smaller form be used than the one shown in the drawing, it is a matter requiring but a moment's time to lower casting 17 until the flange 23 is approximately on a level with the top of the smaller form.

Above and beyond the end of flange 23 the casting 17 mounts a rock shaft 25 revoluble on its axis within the bearing provided by the casting, and carrying at one end a hoop guide finger 27, which turns with the rock shaft. At its extremity the hoop guide finger, which may be tapering as shown in Fig. 1, has a downturned lug 29 which in its normal position may extend below the upper or hoop guiding surface of flange 23, as seen in Figs. 1 and 2 and lie adjacent the edge of said flange so that a hoop may be guided to the stapling head between the finger 27 and the casting 17. Secured to the finger 27 is an extension piece 31 preferably of steel extending over the basket form and normally resting on the upper side thereof so as to bear upon the edge of the basket carried by the form, as shown.

The extension piece being made of flat steel is somewhat resilient. It is arranged above and extends from one side at an angle and bears upon the basket on the form.

The finger extension 31 has an enlarged end or head 33 with an inclined slot 35 provided therein. The body of the extension is preferably about the same width as the hoop, but the head overhangs the hoop and engages the body of the basket on the form, as Fig. 3 discloses. One wall of the slot is

rounded or beveled at 39, and the end of the extension is beveled or rounded at 37 on the under face. (Figs. 4 and 5.) The slot 35 permits the stapling head to drive staples into the hoop, while the latter is held firmly by the finger extension 31, the hoop being held in perfect alinement with the top of the basket until the last staple is driven.

In order to hold down the guide finger 27 and its extension 31, a spring 41 is preferably used, said spring catching under a groove (not shown), provided in a projection 43 of the casting 17 and made fast at the opposite end to rock shaft 25, as indicated at 45. It is desirable to provide means for lifting the guide finger against the resistance of the spring, and one such means as shown may consist of an arm 47 fast at one end to the rock shaft and projecting 20 into the path of movement of a reciprocable rod 49 whose upper end moves in a bore 51 in the casting and whose lower extremity is connected to a suitable operating treadle 53. When the rod 49 is moved upwardly through 25 its connection with the treadle, it will strike arm 47 and thus swing the finger extension 31 away from the form, and also swing the lug 29 away from the guiding flange 23, thereby permitting the operator to remove 30 a finished basket and insert a new hoop or band into the guide from the side for the subsequent stapling operation.

In actual practice, when the foot pedal is depressed, the lug 29 closes the open side 35 of the hoop guide and thereby causes the hoop to remain in a straight line with the top of the basket. When the foot is removed from the pedal, the rod 49 rises and effects the operation previously described.

When using a stapling machine equipped with the invention to make a common berry basket, the operator takes a hoop of requisite length and winds it once about the form 5, a plurality of catches (not shown) being used to hold the hoop temporarily upon the form. This hoop provides the inside band of the basket. I have not disclosed this in detail, as it is not a part of my invention and is well known. Then the operator places the basket web or stock in position over the form and over the inside band, allowing the band to come out through one corner, so as to form the outside band and brings the form under the stapling head. The form is then revolved a partial turn, the band being passed around the outside of the basket, and the stapling mechanism is started so as to fasten together the parts of the basket, including the inside and outside bands, which are formed of one continuous piece. As the form is automatically revolved step by step, the stapling is repeated, each partial rotation of the form drawing the hoop through the guide, and the finger extension 33 always holding the hoop firmly against the basket

at the point where the stapling is done. When the basket has returned to its initial position, the finger extension 33 will hold the free end of the hoop until the last staples are driven.

The finger extension by extending beyond the staple driver guides and holds the hoop after the finishing end of the same gets beyond the lug 29.

The rounded or beveled edge 39 on one 75 wall of the slot prevents slivers on the hoops from catching this edge and causing the hoops to break. The beveled or rounded edge 37 on the end of the extension should be the same or of slightly greater width 80 than the hoop, and it keeps the hoop back against the top edge of the form.

In making a berry basket, it is desirable that the hoop or band be drawn tightly about the basket stock in order that the resultant 85 basket be neat and strong with no bulge at the corners of the basket. It is also desirable that the end of the hoop or band be prevented from springing up above the top of the basket, or down below the line in which the staples are driven, otherwise an unsightly or even an unmarketable basket will be made. The hoop guide described above and shown in the drawing will guide a hoop in a straight line, will draw it tightly around 90 a basket, and will enable the operator to use hoops of the exact length required. This represents a distinct advantage over certain known types of hoop guides in using which 95 hoops must be employed which extend beyond the corners of the basket in order that the hoops may be held in the guides until the last staples are driven.

My invention obviously is not restricted to the particular embodiment thereof herein illustrated and described, which may be varied in form, size and details of construction within the scope of the appended claims.

What is claimed is:—

1. A hoop guide for basket stapling machines having a resiliently mounted hoop holding extension provided with a head, which extends around the staple driver and rests on the hoop prior to and during the driving of the staple, and holds the hoop firmly against the basket where the stapling is done, said guide and extension being adjustably mounted on the machine.

2. A hoop guide for basket stapling machines having a hoop holding extension provided with a head which partially surrounds the staple driver and rests on the hoop prior to and during the driving of the staple, said extension being resilient and arranged above and at one side and at an angle to the form.

3. A hoop guide for basket stapling machines having a hoop holding extension extending around the staple driver to hold the hoop substantially flat against the basket prior to and during the driving of the

staple, and means carrying the hoop guide and its hoop holding extension and adjustable to vary the position of said guide.

4. A hoop guide for basket stapling machines having a hoop holding extension extending around the staple driver to hold the hoop substantially flat against the basket prior to and during the driving of the staple, a spring forcing the extension against the basket, and means controlled by the operator for lifting the extension off the basket.

5. A hoop guide for basket stapling machines, comprising a casting secured to the frame of the machine, a guiding finger pivotally mounted on the casting, and cooperating means on the finger and casting for guiding the hoop to the basket form.

6. A hoop guide for basket stapling machines comprising a casting secured to the frame of the machine, said casting having a hoop guiding flange, and a guiding finger swingably mounted on the casting above the flange and having a depending lug extending to one side of and close to the flange to provide with the casting and flange a guide for the hoop.

7. A hoop guide for basket stapling machines comprising a casting secured to the frame of the machine, a guiding finger pivotally mounted on the casting, and cooperating means on the finger and casting for guiding the hoop to the basket form, said guiding finger having an extension which bears against the hoop and holds the hoop down against the basket stock prior to and during the stapling operation.

8. A hoop guide for basket stapling machines, comprising a casting secured to the frame of the machine, a rock shaft revoluble in the casting, a hoop guide finger turning on the rock shaft, a guiding flange for the hoop on the casting, a lug on the guide finger normally extending below the guiding flange, an extension on the guide finger which bears against the hoop, a spring for holding the guide finger with said lug down and the extension in engagement with the hoop, and means for raising the said extension above the form and swinging the lug away from the guiding flange, thereby permitting the operator to remove a finished basket and insert a new hoop into the guide.

9. A hoop holding member for basket stapling machines pivotally mounted to one side of and above the basket form and having a substantially flat enlarged end provided with a slot therein through which the staple

driving means may operate, said member holding the hoop firmly against the basket where the stapling is being done.

60

10. A hoop guide for basket stapling machines comprising a casting secured to the frame of the machine, a guiding finger pivotally mounted on the casting, and an extension carried by the finger and having an enlarged end or head with a slot therein, said extension holding the hoop firmly against the basket where the stapling is being done.

65

11. A hoop guide for basket stapling machines, having a hoop holding extension resiliently mounted thereon to hold the hoop substantially flat against the basket prior to and during the driving of the staple, said extension having a substantially flat enlarged head with an inclined slot therein through which the staple driving means may operate, said slot extending diagonally across the hoop band.

70

12. A hoop guide for basket stapling machines, having a hoop holding extension to hold the hoop substantially flat against the basket prior to and during the driving of the staple, said extension having a substantially flat enlarged head with an inclined slot therein through which the staple driving means may operate, one wall of the slot being rounded, and the end of said extension presenting guard means to prevent lateral displacement of the hoop.

80

13. A hoop guide for basket stapling machines, having a hoop holding extension to hold the hoop substantially flat against the basket prior to and during the driving of the staple, said extension having a substantially flat enlarged head with an inclined slot therein through which the staple driving means may operate, the end of the extension being beveled or rounded on the hoop engaging face, and the beveled or rounded part being of a width no less than the hoop.

90

14. A hoop guide for basket stapling machines comprising a casting secured to the frame of the machine, a guiding finger pivotally mounted on the casting, and an extension carried by the finger and having an enlarged end or head with a slot therein, said slot being inclined and having one wall beveled or rounded, the end of the extension being also beveled or rounded.

95

In testimony that I claim the foregoing as my own, I have hereto affixed my signature.

105

JOHN EKLUND.
